United States Patent Office.

HENRY S. JANES, OF OSHKOSH, WISCONSIN.

Letters Patent No. 105,215, dated July 12, 1870.

VENTILATOR.

The Schedule referred to in these Letters Patent and making part of the same.

To all whom it may concern:

Be it known that I, HENRY S. JANES, of the city of Oshkosh, State of Wisconsin, have invented a new and improved Room-Ventilator; and I do hereby declare that the following is a full and exact description thereof, reference being had to the accompanying drawing and to the letters of reference marked thereon making a part of this specification.

The nature of my invention consists in the insertion of one or more sheet-metal or iron tubes in a stove-pipe, and in combining therewith an apparatus for regulating the admission of air.

To enable others skilled in the art to make and use my invention, I will proceed to describe its construction and operation.

Figure 1 is a perspective view of an elbow of stove-pipe with my apparatus inserted.

Figure 2 is a vertical longitudinal section, showing the ventilating-tube and the apparatus for regulating the admission of air.

Figure 3 is a perspective view of the apparatus for regulating the admission of air.

A is a stove-pipe elbow.

B is the regulating apparatus inserted in the ventilating-tube.

B' is the prolongation of the regulating apparatus,

and admits of a convenient means of inserting the same in the tube.

B² is the register that regulates quantity or cuts off ventilation.

E E are knobs that afford a convenient means of working the register.

Arrows marked 2 2 show the direction of the hot air and draught.

The register being adjusted for ventilating the room, the arrows marked 3 show the direction of the currents of air escaping from the room.

The tube C being extended into the stove-pipe, with hot air surrounding it, ventilation would be very much accelerated as a natural result.

What I claim as my invention, and desire to secure by Letters Patent, is—

1. The ventilating-tube C, when inserted into a stove-pipe, substantially as and for the purposes set forth.

2. The regulating apparatus B, provided with a tube, B', when used in combination with the ventilating-tube C, as and for the purposes set forth.

HENRY S. JANES.
